HAIR GROOMING COMB

Herman F. Jackson, Detroit, Mich.

Application October 20, 1949, Serial No. 5,608

Term of patent 14 years

(Cl. D86—8)

To all whom it may concern:

Be it known that I, Herman F. Jackson, a citizen of the United States, residing at Detroit, State of Michigan, have invented a new, original, and ornamental Design for a Hair Grooming Comb, of which the following is a specification, reference being had to the accompanying drawing, forming a part hereof.

Fig. 2 is an end view looking from left to right of Fig. 1.

The essential features of my design reside in the portion shown in full lines in the drawing.

I claim:

The ornamental design for a hair grooming comb, as shown and described.

HERMAN F. JACKSON.
